UNITED STATES PATENT OFFICE.

GEORGE T. THOMPSON, OF BREMERTON, WASHINGTON.

TOY.

Application filed July 6, 1921. Serial No. 482,731.

To all whom it may concern:

Be it known that I, GEORGE T. THOMPSON, a citizen of the United States, residing at Bremerton, in the county of Kitsap and 5 State of Washington, have invented certain new and useful Improvements in Toys, of which the following is a specification.

This invention relates to toys and more particularly to toy boats for indoor use.

10 The object of the invention is to provide a toy of the paddle wheel type to be drawn over the floor for the amusement of small children.

Another object is to provide a toy of this 15 character having a paddle wheel so constructed that the drawing of the boat over the floor operates to rotate the wheel and impart to the boat the appearance of a real boat, the blades of which produce a clicking sound when the wheel is so rotated.

With these and other objects in view the invention consists in certain novel features of construction as hereinafter shown, described and claimed.

25 In the accompanying drawing:

Figure 1 represents a side elevation of a toy constructed in accordance with this invention, and,

Fig. 2 represents a top plan view thereof 30 with parts broken out and in section.

In the embodiment illustrated the toy constituting this invention comprises a body 1 preferably constructed of a solid block although not necessarily so the configuration of which is that of a steamboat. This body 1 is provided at its rear end with a pair of longitudinally extending laterally spaced arms 2 between the free ends of which is journaled a paddle wheel 3, washers 4 being mounted between the ends of said wheel and the inner faces of the arms 2 to provide for the free rotation of the wheel without binding on said arms.

The wheel 3 has a plurality of radiating 45 blades 5 any desired number of which may be employed, eight being here shown, and the outer edges of these blades are shown flat or straight throughout their length extending substantially at right angles to their 50 side faces or edges as is shown clearly in Fig. 1 so that when the wheel is rotated the edges of the blades at the perimeter thereof will engage the floor as shown in Fig. 1 so that there will be sufficient friction to 55 rotate the wheel when the boat is drawn over the floor.

The bottom 6 of the body 1 of the boat is arranged substantially in alignment with the perimeter of the blades 5 of the paddle wheel as is shown clearly in Fig. 1 so that 60 when the boat body is drawn over the floor the wheels will engage and rotate the wheel, the clicking sound produced by the rotation of said wheel causing it to more closely resemble a real boat.

65 From the above description it will be obvious that a toy constructed as shown and described herein may be very cheaply manufactured and will afford great amusement for small children indoors especially adapting it for rainy day use.

70 The preferred embodiment of the invention is disclosed in the drawings and set forth in the specification, but it will be understood that any modification within the scope of 75 the claimed invention may be made in the construction without departing from the principle of the invention or sacrificing any of its advantages.

78 What is claimed is:

1. A toy comprising a body member formed from a solid block of material and representing a miniature steamboat adapted to be mounted on and manually shifted over a flat supporting surface, said member having a 80 pair of spaced rearwardly extending longitudinally disposed rigid integral arms at the rear end thereof, and a rotatable paddle wheel journaled between said arms and including blades having angular edges and positioned to contact with the surface on which 85 said body member is manually shifted, causing thereby the rotation of the wheel.

2. A toy comprising a body member formed from a solid block of material and 90 representing a miniature steamboat adapted to be mounted on and manually shifted over a flat supporting surface, said member having a pair of spaced rearwardly extending longitudinally disposed rigid integral arms at the rear end thereof, a rotatable paddle wheel journaled between said arms and including blades having angular edges and positioned to contact with the surface on which 95 said body member is manually shifted, causing thereby the rotation of the wheel, and means for spacing the wheels from said arms.

3. A toy comprising a manually pulled body member representing a miniature 100 steamboat and having a pair of integral spaced arms projecting rearwardly there-

from and adapted to be mounted on and said arms flush with said body and the pulled over a supporting surface, and a blades of the wheel projecting above the paddle wheel mounted to revolve between body. 10
said arm and having the blade thereof positioned to contact with the surface over which the body is pulled, causing thereby the rotation of the wheel, the top edge of

In testimony whereof, I affix my signature hereto.

GEORGE T. THOMPSON.
